SYRINGE

Robert C. Angell, Prince Bay, N. Y., assignor to
The S. S. White Dental Manufacturing Com-
pany, a corporation of Pennsylvania

Application February 13, 1933, Serial No. 656,549

25 Claims. (Cl. 128—257)

My invention relates particularly to that class of syringes that are adapted to be connected with a supply of water under pressure and employed in the practice of dentistry, and is especially applicable to the type of syringe designed to delicately control under manual manipulation the flow of a thermally conditioned fluid, whereby it may be directed at substantially body temperature into the oral cavity at any desired rate of flow.

The principal objects of my invention are to provide a syringe with means therein contained that will generate heat and so induct it into the fluid therein as to insure a continuous flow therethrough of warm fluid from the instant that said syringe is actuated to effect projection of said fluid from its nozzle, and to maintain such flow of warm fluid at a substantially uniform temperature throughout the period of use of said syringe.

Other objects of my invention are to provide a syringe with means to effect instantaneous full flow start and stop of fluid without any attendant drip, to so delicately control the flow of the fluid that it may be either delivered from the nozzle at a maximum capacity stream or in a drop by drop manner; and to so control the stream direction that it may be squirted into the area to be flushed with superior accuracy and precision.

Further objects of my invention are to provide a syringe in which there are no sliding joints, and consequently no packing is required to prevent leakage incident to wear by use or to deterioration by nonuse, thus any tendency to develop fluid leaks is entirely eliminated.

My invention comprehends a syringe in which the constituent parts of the fluid conduit are so yieldingly connected in fluid-tight relation as to permit such relative movement thereof that a valve within said conduit may be actuated to control the fluid flow therethrough by means manipulated from without said conduit.

My invention includes a syringe having a fluid passageway terminating in a nozzle and extending therethrough which forms a continuation of the flexible conduit leading from the source of fluid supply, and which includes sections of flexible tubing formed into readily removable and replaceable cartridge-like units.

My invention provides a syringe adaptable to the employment of readily interchangeable nozzle units such as are shown in United States Patent No. 1,599,998, which may be of any desired length or curvature and provided with any diameter of bore, and which may be so rotated

about its axis as to permit the outlet orifice of its nozzle to be directed at any desired angle with respect to the plane of actuation of the operating or controlling lever of said syringe.

Specifically stated, the form of my invention as hereinafter described comprises a casing or sheath formed of relatively separable tubular members having a nozzle attachment terminal or tip and forming a chamber through which a readily removable and replaceable fluid conduit embracing a heating element extends. Said conduit includes relatively stationary terminal elements and a relatively movable intermediate body carrying a valve into and out of operative engagement with a suitably provided valve seat in the nozzle attachment terminal, the intermediate body being connected in fluid-tight relation with the respective terminal members by relatively short sections of flexible tubing which may respectively be stretched or compressed axially, as the case may be, by axial movement of said intermediate body, by which the valve may be caused to engage or disengage its seat to control the flow of fluid therethrough. The axial movement of said intermediate body may be conveniently effected by a thumb actuated lever mounted to rock in a suitably provided mounting on the syringe casing, and so correlated with interposed connecting means that when said lever is pressed toward the syringe casing the intermediate body will be forced rearwardly to effect withdrawal of the valve from its seat to permit fluid to flow therethrough to be emitted from the syringe nozzle.

My invention also includes all of the various novel features of construction and arrangement as hereinafter more definitely specified.

In the accompanying drawings, Figure 1 is a side elevational view of a syringe constructed in accordance with my invention; Fig. 2 is an enlarged central vertical sectional view of the syringe shown on Fig. 1 taken axially in the plane of its actuating lever, the nozzle and its connector being removed; Fig. 3 is an enlarged horizontal sectional view of the syringe as shown in Fig. 2, taken axially in a plane transverse and normal to the plane of the actuating lever, certain parts being shown in elevation and the nozzle attachment terminal together with the fluid controlling valve being removed for convenience of illustration; Fig. 4 is a plan view of the syringe as illustrated in Fig. 1; Fig. 5 is an enlarged central vertical sectional view of the syringe as illustrated in Fig. 2 but showing the parts shifted by depression of the thumb actuated lever to the operative posi-

tion in which the valve is withdrawn from its seat to permit flow of fluid therethrough; Fig. 6 is a transverse vertical sectional view taken in the planes indicated by the staggered line 6-6 in Fig. 2; Fig. 7 is a transverse vertical sectional view taken on a plane indicated by the line 7-7 in Fig. 2; Fig. 8 is a transverse vertical sectional view taken in a plane indicated by the line 8-8 in Fig. 2; Fig. 9 is a perspective view of the valve 10 plunger per se; Fig. 10 is a perspective view of the forward collar of the rearward yielding conduit connector cartridge structure; Fig. 11 is a perspective view of the rearward collar of said cartridge structure; Fig. 12 is a central vertical longitudinal sectional view of the syringe as shown in Fig. 2, illustrating a modification of the valve actuating mechanism, certain parts being shown in elevation for convenience of illustration; Fig. 13 is a fragmentary vertical longitudinal sectional elevational view of the syringe shown in Fig. 12, with the valve actuating parts in operative position to maintain the valve open; Fig. 14 is a fragmentary plan sectional view taken axially through the central region of the syringe shown in Fig. 12 on the line 14-14 in said figure; Fig. 15 is a transverse vertical sectional view taken on the line 15-15 in Fig. 12; Fig. 16 is a transverse vertical sectional view taken on the line 16-16 in Fig. 12; Fig. 17 is a plan view of the casing in which the valve actuating mechanism shown in Figs. 12 to 16 is enclosed to form a readily removable unit; Fig. 18 is an end elevational view of the casing shown in Fig. 17; Fig. 19 is a central vertical longitudinal sectional elevational view of the syringe as shown in Fig. 2, illustrating a further modification of the valve actuating mechanism; Fig. 20 is a fragmentary vertical longitudinal sectional elevational view of the syringe shown in Fig. 19, with the valve actuating lever 40 and its associated parts in operative position to maintain the valve open; Fig. 21 is a fragmentary plan sectional view of the central section of the syringe taken on the line 21-21 in Fig. 20; Fig. 22 is a fragmentary central vertical sectional view showing the rear end portion of the forward casing shell with the rearward casing shell removed and the valve operating lever shifted to the position to clear the internal operative parts and thereby permit their free removal; Fig. 23 is a transverse vertical sectional view taken on the line 23-23 in Fig. 20; Fig. 24 is a perspective view of the valve actuating slide block, as shown in Figs. 19 to 23 inclusive; and Fig. 25 is a fragmentary central vertical sectional view taken axially through the syringe nozzle and its connector and showing its means of attachment to the terminal tip of the syringe body, which is shown in elevation for convenience of illustration.

In said figures, the casing or sheath 1 comprises the forward tubular shell 2 and the rearward tubular shell 3 connected together by the screw threads 5 in such relation that the internally threaded rear end 6 of the shell 2 extends into the forward end of the shell 3, the opposite rotation of said shells 2 and 3 for relative engagement and disengagement being facilitated by the knurled bands 7 and 8 on the shell 2 and the knurled band 9 on the shell 3, as best shown in Figs. 1 and 4.

The forward end of the shell 2 is provided with the internal screw threads 10 with which the nozzle supporting terminal or tip 11, having the tapering free end 12, is threadedly engaged, said tip 11 being provided with the external screw

threads 14, and having at its inner end the internally screw-threaded enlarged bore 13 forming the valve chamber 15 with which the outlet passageway 16 communicates through the valve seat 17.

Said valve seat 17 is formed of an annulus 19 of resilient material, such as soft rubber, mounted with a tubular thimble 20 which maintains the valve seat forming material in its proper form and prevents it from mushrooming or otherwise 10 distorting when being forced into and seated in the counterbore 21 adjoining the valve chamber 15. The inner surface of the bore of the annulus 19 is also protected and held to form by the liner tube 22, preferably formed of metal, said 15 tube terminating short of the inner wall of said annulus, and projecting forwardly into the passageway 16, thereby assisting in stabilizing said valve seat forming annulus 19, but leaving the valve seat 17 freely resilient.

Cooperative with the valve seat 17 is the valve plunger 23 comprising a recessed hollow body 25, having opposed slits 26 extending forwardly from its open end and having fluid exit ports 27 extending from its recess 29 through its forward conical wall 30. As shown in Figs. 2, 5 and 9, the conical wall 30 merges into a forward conical projection 31 of much less angle of taper than the conical wall 30, which projection 31 terminates in the forwardly extending cylindrical stem 32 having 30 the transverse screw-driver slot 33 in its free end.

It may be here noted that the valve plunger 23 is shaped intermediate of its ends to form contiguous relatively tapered distinctly separate conical surfaces, the conical surface of lesser taper 35 extending within the valve seat 17 and being effective to control the rate of flow through the valve when opened, while the conical surface of greater taper serves to press upon the edge of the bore of the valve seat 17 for effectively closing 40 said bore and stopping the flow of fluid therethrough.

The hollow slotted body 25 of the valve plunger 23 is provided with the external screw-threads 35 by which it is engaged with the internally 45 threaded forward end of the valve actuating plunger tube 36 providing a conduit which extends rearwardly into the casing or sheath 1, and mounted for axial reciprocation.

Said plunger tube 36 is provided with external 50 enlargements of varying longitudinal extent which afford the flanges 37, 39 and 40, and terminates approximately at the longitudinal center of the rearward casing shell 3, and is also provided with the external screw-threads 41 disposed forward of but adjacent to the flange 37, and the external screw-threads 42 disposed rearward of but adjacent to the flange 40, the purpose of which flanges and screw threads will be 55 hereinafter described.

The forward tubular shell 2 of the casing or sheath 1 is provided with a sleeve or tubular liner 43 having an inturned flange 45 at its inner or back end providing a bearing in which said 65 plunger tube 36 slides and affording an abutment surface 46, and an outturned flange 47 at its forward end seated in the annular recess 49 in said shell 2 and held rigidly by the nozzle supporting tip 11 against the shoulder 50 formed 70 by said recess.

The plunger tube 36 is slidably supported toward its forward end in the collar 51 having the forward threaded extension 52 in threaded engagement with the casing terminal or tip 11 and 75

thereby secured thereto in fluid-tight relation against the packing gasket 53 of soft yielding material disposed in the annular recess 55 provided therefor in the inner face of said tip 11.

5 Said collar 51 is provided with the rearwardly extending relatively reduced nipple 56 having the circumferential bead 57 and also having the longitudinally disposed recesses 59 in effect forming fingers 60 of which two are indicated, although 10 obviously one or several may be employed with equal facility.

Opposed to the collar 51, and in cooperative, relatively movable relation therewith, is the collar 61 which is provided with the forwardly extending relatively reduced nipple 62 having the circumferential bead 63 and also having the longitudinally disposed recesses 65 forming fingers 66 which relatively interengage with the fingers 60 of the collar 51 by entering the recesses 59 of 15 said collar, to in effect form a longitudinally expandable and collapsible cage.

The collar 61 is internally screw-threaded and engaged with the screw-threads 41 on the plunger-tube 36, and has the annular recess 67 forming a seat for the packing gasket 68 of soft yielding material which when pressed against the shoulder 70 formed by the flange 37 affords a fluid-tight seal.

As shown in Figs. 2, 3 and 5, the nipples 56 and 62 of the respective collars 51 and 61 are connected in relatively movable fluid-tight relation by the short length of soft rubber tubing 71 surrounding the cage formed by the interengaging fingers 60 and 66 and having its respectively opposite ends engaged with the nipples 56 and 62 respectively by the clamp bands or binders 72 and of any desired construction or material.

In order to support the soft rubber tube 71 and to prevent an appreciable expansion in diameter due to the effect of fluid pressure within the syringe, said tube is surrounded throughout its length by the helical wire coil 75 which not only serves as a support for the tube 71 but affords a metal to metal sliding contact with the inner cylindrical wall of the tubular line 43, and thereby facilitates the longitudinal elongation and contraction of said tube 71 when said collars 51 and 61 are relatively shifted.

The structure thus described comprising the collars 51 and 61 and their connecting short length of tubing 71 forms a readily removable and replaceable unit that may be appropriately termed a fluid seal cartridge structure of which two of similar construction are included in the syringe assembly.

The second fluid seal cartridge is located toward the back end of the syringe casing and within the axially adjustable sleeve or tubular liner 76 which is in threaded engagement with the internal screw-threads 77 in the rear end of the tubular casing shell 2 and extends rearwardly therefrom into the tubular casing shell 3, and terminates in the inturned flange 79.

The second or rearwardly disposed cartridge structure comprises the collar 81 having the flange 82 slidably fitting in the liner 76, and the forwardly projecting boss 83 serving as a nut and provided with a plurality of circumferential flats 85, see Fig. 10, affording wrench holds by which said collar may be rotated to engage its internally disposed threads 86 with the screw-threads 42 on the plunger tube 36, and force it against the flange 40 with the interposed leak-proof gasket 87 disposed in the annular recess 88 in the forward face of said collar.

Projecting rearwardly from said flange 82, said collar 81 is provided with a reduced nipple 89 having the bead 90 and being provided with longitudinally extended recesses 91 forming the circumferentially disposed fingers 92, similar to the 5 fingers 60 on the collar 51 of the forward fluid seal cartridge.

Opposed to the collar 81 and in cooperative relatively movable relation therewith is the collar 93, see Fig. 11, which is provided with the forwardly extending relatively reduced nipple 94 having the circumferential bead 95, and also having the longitudinally disposed recesses 96 forming fingers 97 which enter the recesses 91 and relatively interengage with the fingers 92, to in 15 effect form a longitudinally expansible and collapsible cage.

Said collar 93 includes the rearwardly extending flanged boss 98 serving as a nut and provided with a plurality of circumferential flats 99 affording wrench holds by which said collar may be rotated to engage its internally disposed screw-threads 100 with the threaded forward end of the hose connector 101 and thereby draw the forward shoulder of said hose connector into 25 fluid-tight engagement with the interposed gasket 102 disposed in the annular recess 103 in the rearward face of said collar 93. The collars 81 and 93 are connected to form a fluid seal cartridge in a manner similar to the formation of 30 the forwardly disposed cartridge, and embodies the soft rubber tubing 71, clamp bands or binders 72 and 73 and the protective helical wire coil 75, and therefore, detailed description of those parts 35 will not be here duplicated.

As shown in Figs. 2 and 5, the collar 93 is retained and limited against rearward movement by engagement of its flange 104 with the inturned flange 79 of the liner 76 so as to resist the strain incident to the drag of the flexible hose pipe 105, 40 which is engaged with the nipple 106 and connects the fluid passageway 107 extending through the syringe, with any suitable source of fluid supply under pressure.

As shown, particularly in Figs. 2, 5, 6, 7 and 8, 45 the syringe is provided with an elongated heat radiating element 109 extending through the flexible hose pipe 105 and continuing through the passageway 107 and terminating near the forward end of said conduit. Said heat radiating element 50 comprises an elongated slender flexible body formed of insulating material, preferably vulcanized rubber, through which an electric current conductor 110, preferably composed of a plurality of wire strands so as to render it flexible, 55 extends.

Attached to the forward end of said conductor 110, preferably by solder, is a strand of electrical resistance wire 111, of gold or other suitable metal, extending therefrom through the wall of the insulator forming the heat radiating element and being helically coiled thereabout in direct contact with the fluid in the passageway 107, and so connected as to complete the electric circuit to effect heating of said helically coiled resistance wire 111. A soft rubber tip 112 is vulcanized over the end of the heat radiating element 109 after the conductor 110 and the resistance wire 111 have been connected, to prevent the fluid from contacting with said conductor 110.

In order to prevent the short circuiting of the electrical resistance wire 111 by metallic contact with the wall of the conduit-forming plunger tube 36, said tube is provided with the tubular lining 113 of electrical resistance material, which 75

extends forwardly of the forward end of the heat radiating element 109 and projects rearwardly through the hose pipe connector 101 and into the hose pipe 105, as shown in Figs. 2 and 5. Said tubular lining is provided with the enlarged band 5 forming a flange 114 affording a shoulder which bears against the back end of the plunger tube 36 and said tubular lining is of such internal diameter as to afford a substantial annular passageway through which the fluid being heated 10 may pass to the syringe nozzle.

The mechanism by which the valve is actuated is located substantially central with respect to the length of the syringe and comprises the 15 inverted saddle-like shoe or slide-block 115 embracing the plunger tube 36 and provided with the transverse groove 116, extending throughout its U-shaped inner surface, see Fig. 7, into which groove the flange 39 on said plunger tube 36 extends, and said slide-block has the upwardly and 20 rearwardly inclined forwardly disposed inclined surface 117 upon which the wedge-block 119 slides.

Said wedge-block 119 comprises the saddle-like 25 structure having the correspondingly inclined surface 120 which slides upon said inclined surface 117 and having its forward end slidingly abutted against the rear surface 122 of the tubular liner 43 in transversely slidable relation therewith, said 30 slide-block 119 being provided with the longitudinally directed groove 123 in its upper surface.

It will be obvious that any depression of the 35 wedge-block 119 tends to cause relative sliding of the opposed inclined surfaces 117 and 120 of the slide-block 115 and wedge-block 119 respectively, which effects rearward movement of said slide-block 115 and consequently a like movement 40 of the plunger tube 36 and the valve plunger 23 carried thereby, in opposition to the spring 125 to effect withdrawal of said valve plunger 23 from its seat 17.

The spring 125 surrounds the elongated flange 37 on the plunger tube 36 and bears at its 45 respectively opposite ends against the inturned flange 45 of the tubular liner 43 and the collar 61, thereby normally tending to shift the plunger tube 36 forwardly to close the valve plunger 23 against the valve seat 17.

Actuation of the valve controlling mechanism 50 is conveniently effected by pressing downward on the thumb actuated lever 126, which is arranged to rock on the pintle 127 carried by the ears or lugs 129 on the band 130 which girdles the inner 55 end portion of the tubular shell 2 of the casing 1. Said lever 126 is provided with the depending pin or projection 131 extending into the groove 123, and having its rounded free end so engaging the wedge-block 119 as to force it downwardly and by reason of its sliding engagement with the 60 abutment surface 46 and the cooperation of its inclined surfaces 120 with the opposed inclined surfaces 117 on the slide-block 115, all of the parts connected with said slide-block will be moved rearwardly therewith to open the valve. Upon release of the lever 126, all of said parts 65 will be reversely shifted by the spring 125 to effect closing of said valve.

As shown in Figs. 2 and 7, the pintle 127 has 70 the waist 133 into which the set-screw 135 extends so as to prevent accidental displacement of said pintle by reason of the rocking action of the lever 126 which is provided with the pocketed spring pressed plunger 136 tending to 75 rock the lever 126 forwardly to constantly main-

tain the pin or projection 131 in operative engagement with the wedge-block 119.

Any desired form of nozzle 131 may be employed in connection with the syringe assembly herein shown and described, but the nozzle connector 5 138, illustrated in Figs. 1, 4 and 25, is embodied in United States Patent No. 1,599,998, and therefore its detailed description is deemed to be unnecessary; however, it will be further referred to hereinafter. 10

It may be here noted that by reason of the yielding fluid-tight connection afforded by the fluid seal cartridge units, the valve which is wholly contained within the fluid conduit may be readily and delicately controlled from without 15 said conduit in such manner as to avoid the employment of any sliding joints that require to be periodically packed, or otherwise repaired, and that might at any time leak and cause irreparable damage and possible embarrassment to both the 20 operator and patient.

The syringe embodying the modified form of 25 my invention, as illustrated in Figs. 12 to 18 inclusive, is generally similar to the syringe illustrated in Figs. 1 to 11 inclusive except that the valve actuating mechanism is so encased to prevent the relative separation of its constituent parts, which permits said parts to be removed from and replaced in the syringe casing as a unit.

Enclosed within the syringe casing 139 comprising the forward tubular shell 140 having the flanged liner 141, and the rearward tubular shell 142 having the flanged liner 143, is the reciprocatory valve actuating plunger tube 145 which both serves as a conduit to convey fluid through 35 the syringe and effects opening and closing of the valve depending upon its direction of movement, as in Figs. 2 and 5. 30

Said plunger tube 145 is provided with the collar 146 having the flange 147 snugly fitted for 40 reciprocation in the liner 141, and the collar 149 having the flange 150 snugly fitted for reciprocation in the liner 143, and said plunger tube 145 is also provided with the circumferential flange 151 intermediate of said collars 146 and 149. 45

The mechanism by which the valve operating plunger tube 145 is actuated comprises the saddle-like shoe or slide-block 152 embracing the plunger tube 145 and having the transverse groove 153, 50 extending throughout its U-shaped inner surface, and into which the flange 151 extends. Said slide-block 152 has the forward inclined surface 155 upon which the wedge-block 156 slides.

Said wedge-block 156 comprises the saddle-like structure having the correspondingly inclined surface 157 which slides upon said inclined surface 155 and having its forward end slidingly abutted against the rear surface 159 of the annular collar 160 to which the tubular sub-casing 161 is secured by the rivet 162, to provide a container for the valve actuating mechanism, and by which its constituent parts are retained on the plunger tube as a unit. 55

As shown particularly in Figs. 14 to 18 inclusive, the collar 160 is provided with rearwardly extending peripherally disposed segmental projections 163 fitted into corresponding recess 164 in the tubular sub-casing 161, and said collar is also provided with diametrically opposite channels 165 into which the forwardly projecting extensions 166 are fitted, through one of which the rivet 162 extends, see Figs. 17 and 18. 65

The sub-casing 161 of the valve actuating mechanism is provided with the longitudinally extended slot 167 which registers with a similarly 70 75

directed slot 169 in the forward shell 140, and through which said registered slots 167 and 169 the depending projection 170 of the thumb lever 171 extends into operative engagement with the 5 wedge-block 156, whereby it may be forced downwardly, and by cooperation of the opposed inclined surfaces 155 and 157, the slide-block 152 and plunger tube 145 are forced rearwardly to effect opening of the valve.

10 The thumb actuated lever 171 is mounted to rock on the pintle 172 extended through suitably provided alined apertures in the ears or lugs 173 which project upwardly in parallel relation from the band 175 girdling the forward casing shell 15 140.

The forward end of the tubular sub-casing 161, and its associated collar 169, abut against the rear end of the flanged liner 141 and is prevented from rotation or being forced rearwardly by the 20 set-screw 176 which has its head embedded in the countersunk aperture 177 in the wall of the casing shell 140, and which extends in threaded engagement with the collar 160.

The collar 160 affords an abutment for the 25 spiral spring 179 which bears at its forward end against the collar 146 and thereby tends to thrust the plunger tube forwardly to close the valve and to return the valve actuating lever 171 and its associated parts, including the slide-block 152 30 and wedge-block 156, from the open valve position shown in Fig. 13 to the closed valve position shown in Fig. 12.

It may be here noted that in this form of my 35 invention, removal of the internal working parts of the syringe for repair or replacement may be conveniently effected after removal of the set-screw 176, and that by reason of the fact that the slide-block 152 and wedge-block 156 are enclosed in the sub-casing 161, they are prevented 40 from accidental separation and are maintained intact with the plunger tube 145 until such time as the sub-casing 161 has been slipped forwardly therefrom.

The syringe embodying a further modified form 45 of my invention, as illustrated in Figs. 19 to 24 inclusive, is similar in most respects to the syringe illustrated in Figs. 1 to 11 inclusive and hereinbefore described except as applied to valve actuating mechanism to which the description immediately following will specifically apply.

Enclosed within the syringe casing 181 comprising the forward tubular shell 182, having the longitudinal slit 183, and the rearward tubular shell 185 connected together by the screw threads 55 186, and partially covering said slit 183, is the valve actuating plunger tube 187, having the flange 189, and mounted to reciprocate in the tubular liner 190 having the inturned flange 191 affording an abutment and also providing a slide 60 bearing for said plunger tube 187 which is normally thrust forwardly to close the valve of the syringe by the helically coiled spring 192.

Mounted upon the plunger tube 187, between the abutment flange 191 and the flange 189, is a 65 saddle-formed block 193, best shown in perspective in Fig. 24, and comprising the elongated aperture 195, in its uppermost wall, against the rear end surface of which the depending hook-like finger 196 depending from the thumb operated lever 197 bears.

Said thumb operated lever 197 is mounted to rock on the pintle 199 which extends through suitably alined apertures in the ears or lugs 200 and which is prevented from accidental displacement by the set-screw 201 having the pocket

202 for the spring 203 which so tends to rock the lever 197 as to maintain the finger 196, which extends through the longitudinally disposed slit 183, in engagement with said block 193. Said ears or lugs 200 project upwardly from the band 5 205 which girdles the rearward end of the forward tubular shell 182 of the syringe casing 181.

In the normally inoperative or closed valve position of the syringe parts, as shown in Fig. 19, the block 193 rests against the abutment 10 flange 191, as shown in Fig. 19, but any downward movement of the lever 197 causes the finger 196 to rock through the slit 183 in an arc about the axis of the pintle 199 and thereby shifts the block 193 rearwardly in contact with 15 the flange 189 to retract valve actuating plunger tube 187 in opposition to the spring 192, as indicated in Fig. 20.

The movement of the lever 197 beyond its normally inoperative position is limited by the 20 buffer 206 provided by extending the rear end of said lever downwardly to engage the tubular shell 185 of the syringe casing 181, and in such position, as will be obvious, the internal parts of the syringe could not be withdrawn for repair 25 or replacement, due to the fact that the finger 196 extends into the path of the block 193.

As illustrated in Fig. 22, the slit 183 is of such longitudinal extent that when the rearward tubular shell 185 is backed off or removed from 30 the forward tubular shell 182, the lever 197 may be rocked into such position that both the finger 196 and the buffer 206 of said lever terminate within the slit 183 and so free the parts within the casing 181 as to permit them to be readily 35 withdrawn forwardly therefrom.

In the form of my invention illustrated in Figs. 19 to 24 inclusive, the actuation of the lever 197 effects a direct axial rearward thrust of the block 193 against the flange 189 of the valve 40 actuating plunger tube 187 and thereby tends to simplify the construction by elimination of the inclined plane sliding action of the slide-block and wedge-block, as hereinbefore described.

As illustrated in Fig. 25, the nozzle 137 and 45 its connector 138, hereinbefore briefly referred to, is detachably connected with the terminal tip 11, said connector being threadedly engaged with the screw threads 14 thereon. The nozzle 137 has the enlarged counter-bore 209 tapered 50 to snugly fit the forward tapered free end 12 of the terminal tip 11 upon which it is tightly held by the fingers 210 and 211 of said connector 138 engaging the shoulder 212 formed by the enlarged head or flange 213 at the back 55 or inner end of said nozzle 137.

It may be here noted that although the nozzle 137 is so tightly held on the terminal tip 11 by the fingers 210 to afford a leak-tight joint, it is obvious that as the shoulder 212 encircles 60 the nozzle body, said nozzle may be rotated relative to the terminal tip 11 to direct its deflected end, and consequently, the stream of fluid emitted therefrom in any desired direction.

My invention is advantageous in that all of 65 the relatively movable sections or parts of the syringe structure through which the fluid is directed are so rigidly connected in fluid-tight relation that the possibility for leakage of the fluid passing therethrough is reduced to a minimum; furthermore, the fluid conduit sections and syringe parts are so correlated that they may be readily taken apart and assembled so as to afford easy repair and replacement.

I do not desire to limit my invention to the 75

precise details of construction and arrangement as herein set forth, as it is obvious that various modifications may be made therein without departing from the essential features of my invention as defined in the appended claims.

Having thus described my invention, I claim:

1. A syringe of the class described, having a conduit forming a fluid passageway and comprising a plurality of relatively movable sections having their adjacent ends relatively separated and yieldingly connected in fluid-tight relation to form an imperforate fluid conveyer, and a valve connected with one of the sections and arranged to be actuated to open or close said passageway by relative movement of said section.
2. A syringe of the class described, having a conduit forming a fluid passageway and comprising a plurality of relatively movable sections having their adjacent ends relatively separated and yieldingly connected in fluid-tight relation to form an imperforate fluid conveyer, a valve connected with one of the sections and arranged to be actuated to open or close said passageway by relative movement of the section to which said valve is connected, and means arranged to move said section.
3. A syringe of the class described, having a conduit forming a fluid passageway therethrough and comprising a plurality of relatively movable sections having their adjacent ends relatively separated and yieldingly connected in fluid-tight relation, a valve in said passageway connected with one of said sections and arranged to be actuated to open or close said passageway by relative movement of said section, a casing enclosing said conduit, and manually actuated means mounted on said casing operative to effect movement of the movable section to which said valve is connected.
4. A syringe of the class described, having a casing provided with a valve seat and having a fluid-tight conduit extending through said casing and forming a fluid passageway therethrough, said conduit comprising a plurality of relatively movable sections having their adjacent ends relatively separated and yieldingly connected in fluid-tight relation, a valve plunger connected with one of said sections and arranged to be actuated to engage or disengage said seat to effect opening or closing of said passageway by relative movement of said section, means comprising relatively slideable members embracing said conduit and having opposed inclined surfaces cooperatively associated to effect movement of said movable section, and manually actuated means mounted on said casing arranged to effect such relatively sliding movement of said members and consequent movement of said movable section and its connected valve plunger.
5. A syringe of the class described, having a conduit forming a fluid passageway therethrough and comprising a plurality of alternately rigid and yielding relatively movable sections having their adjacent ends relatively separated and yieldingly connected in fluid-tight relation, a valve connected with one of the sections and arranged to be actuated to open or close said passageway by the relative movement of said section.
6. A syringe of the class described, having a fluid-tight conduit affording a fluid passageway and comprising a plurality of relatively movable sections yieldingly secured together in relatively separated relation to form sealed joints between each section, and a valve controlling said pas-

sageway and connected with one of the sections.

7. A syringe of the class described, comprising a conduit affording a fluid passageway connecting a source of fluid supply with its nozzle and having relatively movable component parts yieldingly joined in relatively separated fluid-tight relation at their region of junction, fluid controlling means in said passageway connected with a movable part of said conduit and effective by movement of said part to open or close said passageway whereby delicate control of the fluid is afforded without any sliding or packed joints.

8. A syringe of the class described, comprising a conduit affording a fluid passageway connecting a source of fluid supply with its nozzle and having relatively movable component parts yieldingly joined in relatively separated fluid-tight relation at their region of junction, fluid controlling means in said passageway connected with a movable part of said conduit and effective by movement of said part to open or close said passageway, and manually actuated means arranged to effect movement of said movable part of said conduit.

9. A syringe of the class described, comprising a conduit affording a fluid passageway connecting a source of fluid supply with its nozzle and having relatively movable component parts yieldingly joined in relatively separated fluid-tight relation at their region of joining, fluid controlling means in said passageway connected with a movable part of said conduit and effective by movement of said part to open or close said passageway, means tending to yieldingly move said conduit part into position to effect closing of said passageway, and manually actuated means comprising relatively slideable saddle-like blocks embracing said conduit and arranged to move said conduit part to effect opening of the said passageway.

10. A syringe of the class described, comprising a conduit affording a fluid passageway connecting a source of fluid supply with its nozzle and having relatively movable component parts yieldingly joined in fluid-tight relation to form an imperforate fluid conveyer, fluid controlling means in said passageway connected with a movable part of said conduit and effective by movement of said part to open or close said passageway, a casing embracing said conduit, manually actuated means mounted on said casing operatively connected to effect movement of said movable part of said conduit whereby delicate control of the fluid is afforded without any sliding or packed fluid-conveying joints.

11. A syringe of the class described, comprising a casing having a terminal outlet tip affording a valve seat, a conduit extended through said casing and having relatively movable component parts yieldingly poined in fluid-tight relation to connect a source of fluid supply with the terminal outlet, a valve plunger cooperative with said valve seat to control the flow of said fluid and connected with a movable part of said conduit to move therewith, and manually actuated means mounted on said casing and projecting through its wall into cooperative relation with said movable part of said conduit operative to effect relative movement of said valve plunger and its seat.

12. A syringe of the class described, comprising a casing having a terminal outlet tip affording a valve seat, a conduit extended through said casing and having relatively movable component parts yieldingly joined in fluid-tight relation to

connect a source of fluid supply with the terminal outlet, a valve plunger cooperative with said valve seat to control the flow of said fluid and connected with a movable part of said conduit to be moved therewith, means having an inclined surface mounted to move with said movable part, and manually operative means slidably cooperative with said inclined surface effective to move said movable part and consequent relative movement of said valve plunger and its seat.

13. A syringe of the class described, comprising a casing having a terminal outlet tip affording a valve seat, a conduit extended through said casing and having relatively movable component parts yieldingly joined in fluid-tight relation to connect a source of fluid supply with the terminal outlet, a valve plunger cooperative with said valve seat to control the flow of said fluid and connected with a movable part of said conduit to be moved therewith, a slide-block having an inclined surface movable with said movable part, a wedge-block transversely movable in said casing and arranged to slide on said inclined surface to effect longitudinal movement of said movable part and valve plunger, and manually actuated means mounted on said casing cooperative to effect transverse movement of said wedge-block and consequent longitudinal movement of said slide-block and the movable parts associated therewith.

14. A syringe of the class described, comprising a casing having a terminal outlet tip provided with a valve-seat, a conduit extending through said casing and having relatively movable component parts yieldingly joined in fluid-tight relation to connect a source of fluid supply with the terminal outlet, a valve plunger cooperative with said valve-seat to control the flow of said fluid and connected with a movable part of said conduit to be moved therewith, yielding means tending to thrust said valve toward its seat to close said passageway, a manually actuated lever mounted to rock on said casing and having a projection extending into said casing, and means cooperatively interposed between said projection and movable part of said conduit, operative when said lever is manually actuated, to effect movement of said valve plunger from its seat in opposition to said yielding means.

15. A syringe of the class described, comprising a casing having a terminal outlet tip provided with a valve-seat, a conduit extending through said casing and having relatively movable component parts yieldingly joined in fluid-tight relation to connect a source of fluid supply with the terminal outlet, a valve plunger cooperative with said valve-seat to control the flow of said fluid and connected with a movable part of said conduit to be moved therewith, yielding means tending to thrust said valve toward its seat to close said passageway, a manually actuated lever mounted to rock on said casing and having a projection extending into said casing, and means cooperatively interposed between said projection and movable part of said conduit, operative when said lever is manually actuated, to effect movement of said valve plunger from its seat in opposition to said yielding means, and a sub-casing surrounding said cooperatively interposed means arranged to hold said means captive with said conduit when it is removed from its casing.

16. A syringe of the class described, comprising a casing having a terminal outlet tip provided with a valve-seat, a valve plunger cooperative

with said seat and carried by a conduit extending through said casing to connect a source of fluid supply with the terminal outlet, and comprising the central tube mounted for slight reciprocation in said casing and provided with relatively spaced collars secured thereon in fluid-tight relation in opposition to similar collars relatively spaced therefrom and held in rigid relation with said casing, flexible tubing connecting the opposed collars in fluid-tight relation and permitting the reciprocatory movement of said tube to open and close the valve, and manually actuated means connected with said tube to effect its reciprocation and thereby control the fluid flow therethrough.

17. A syringe of the class described, comprising a casing embracing a fluid-tight conduit including inlet and outlet sections in stationary relation with said casing, and an intermediate relatively movable section connected with the respective inlet and outlet sections by fluid-tight cartridge-like units formed of flexible tubing and each having a collar engaged with said intermediate section and one having a collar engaged with said inlet section and the other having a collar engaged with said outlet section, means carried by said intermediate section to control the flow of fluid through said conduit, and manually actuated means carried by said casing cooperative with said intermediate section to effect its movement.

18. A syringe of the class described, comprising a casing embracing a fluid-tight conduit including inlet and outlet sections in stationary relation with said casing, and an intermediate relatively movable section connected with the respective inlet and outlet sections by fluid-tight cartridge-like units formed of flexible tubing and each having a collar engaged with said intermediate section and one having a collar engaged with said inlet section and the other having a collar engaged with said outlet section, means carried by said intermediate section to control the flow of fluid through said conduit, and manually actuated means carried by said casing cooperative with said intermediate section to effect its movement and an elongated heating element extending through said conduit and terminating close to said outlet section.

19. A syringe of the class described, comprising a casing embracing a fluid-tight conduit including inlet and outlet sections in stationary relation to the casing, and an intermediate relatively movable section connected with the respective inlet and outlet sections by cartridge-like units of flexible tubing respectively having their relatively opposed ends rigidly connected in fluid-tight relation to the oppositely directed ends of said intermediate section and their relatively oppositely directed ends rigidly connected in fluid-tight relation, one to the inlet section and the other to the outlet section, and means carried by said intermediate section arranged to control the flow of fluid through said conduit in accordance with the axial movement of said intermediate section with respect to the other sections.

20. A syringe of the class described, comprising inlet and outlet sections and an intermediate relatively movable section connected with the respective inlet and outlet sections by flexible tubing one having its respective ends bound in fluid-tight relation to the opposed ends of said inlet and intermediate sections and the other having its respective ends bound in fluid-tight

relation to the opposed ends of said intermediate and inlet sections, means tending to advance said intermediate section and means connected with said intermediate section arranged to control the flow of fluid through said conduit in accordance with the axial movement of said intermediate section with respect to the other sections.

21. A syringe of the class described, comprising a casing, an outlet section and a relatively movable section inclosed in said casing and having their relatively opposed ends connected by a section of flexible tubing bound tightly to said opposed ends to form a continuous conduit, and means actuated by the relative movement of said sections to control the flow of fluid through said conduit.

22. A syringe of the class described, comprising a continuous imperforate tubular conduit formed of a plurality of relatively movable sections yieldingly connected and sealed together to afford a non-leakable fluid conveyer, a valve seat within said conduit, a valve connected with one of said sections arranged to be moved thereby into and out of engagement with said seat, and means exterior to said conduit connected to relatively move said sections where said valve may be actuated to open or close said valve.

23. A syringe of the class described, comprising a casing embracing a fluid-tight conduit including inlet and outlet sections in stationary relation with said casing, and an intermediate relatively movable section connected with the respective inlet and outlet sections by fluid-tight cartridge-like units formed of flexible tubing and each having a collar engaged with said intermediate section and one having a collar engaged with

said inlet section and the other having a collar engaged with said outlet section, means carried by said intermediate section to control the flow of fluid through said conduit, and manually actuated means carried by said casing cooperative with said intermediate section to effect its movement, and an elongated heating element extending into said conduit.

24. An article of manufacture, comprising a valve controlled conduit, the combination with relatively spaced conduit sections, of a valve-seat, a relatively movable conduit section disposed between said spaced sections, sections of elastic tubing connecting said spaced and movable sections and by reason of their elasticity permitting a limited axial movement of said movable section with respect to said relatively spaced sections, and a valve cooperative with said valve-seat to control the flow of fluid through said conduit, said valve being connected to be actuated by the relative axial movement of said movable section to effect its opening and closing with respect to said seat.

25. An article of manufacture, comprising a valve controlled conduit, the combination with relatively stationary and movable conduit sections, of a valve-seat disposed in one of said sections, a section of elastic tubing connecting said stationary and movable sections with its ends rigidly secured to the opposed ends of said sections, and a valve connected with the other of said sections and arranged to be actuated by the relative movement of said sections to open and close with respect to said seat, and thereby control the flow of fluid through said conduit.

ROBERT C. ANGELL.
